Primary Examiner — Elizabeth Albert*(74) Attorney, Agent, or Firm* — Holtz, Holtz, Goodman & Chick PC(57) **CLAIM**

The ornamental design for a sorter and writing implement holder, as shown and described.

DESCRIPTION

FIG. 1 is a front, right side, top perspective view of a sorter and writing implement holder showing my new design;
FIG. 2 is a front, left side, top perspective view thereof;
FIG. 3 is a front elevational view thereof;
FIG. 4 is a rear elevational view thereof;
FIG. 5 is a right side view thereof;
FIG. 6 is a left side view thereof;
FIG. 7 is a top plan view thereof;
FIG. 8 is a bottom plan view thereof; and,
FIG. 9 is a sectional view thereof taken along line 9-9 in FIG. 5.

The broken lines in the drawings are included for the purpose of showing portions of the sorter and writing implement holder that form no part of the claimed design.
